A. KRAKAUER

SELF LOCKNG SPRNG

Filed Feb. 6. 1924

FIG. 1

FIG. 3

FIG. 4

INVENTOR
Abraham Krakauer
BY
Harry Jackson
ATTORNEY

UNITED STATES PATENT OFFICE.

ABRAHAM KRAKAUER, OF BROOKLYN, NEW YORK.

SELF-LOCKING SPRING.

Application filed February 6, 1924. Serial No. 690,896.

To all whom it may concern:

Be it known that I, ABRAHAM KRAKAUER, a citizen of the United States, residing at the city of New York, in the county of

5 Kings and State of New York, have invented certain new and useful Improvements in Self-Locking Springs, of which the following is a specification.

This invention relates to the mounting of 10 coil springs such as are used in upholstered seats, cushions and furniture. The invention is concerned primarily with the support on to which said springs may be quickly and easily mounted and locked into place 15 in variable spaced relation by a simple movement.

In the drawings, Fig. 1 is a perspective view of my invention showing a series of 20 springs locked in place. Fig. 2 is top plan view of a portion of Fig. 1 showing a coil spring secured in position on a flat supporting strip. Fig. 3 is a vertical section of the line 3—3 of Fig. 2. Fig. 4 is a similar section on the line 4—4 of Fig. 2 and Fig. 5 is 25 a perspective view of my invention as applied to a cross bar.

In mounting coil springs as 10 for use in the backs and seats of chairs or other upholstery, it is desirable to provide a firm 30 base for supporting the springs on which base the pressure due to the compression of the spring is exerted, while at the same time maintaining the spring against displacement or danger of accidental removal from 35 the mounting therefor.

It will be understood that there are two important types of supporting members in use for supporting coil springs, that is, a flat strip as 12, used mainly for upholstered 40 backs, and a shaped cross bar as 13, used mainly for seats. My improved mounting is adapted to both types of support. Said mounting comprises, in brief, an arch-shaped projection as 11, substantially of the 45 same thickness as the material of the support, pressed outwardly from the support itself to a sufficient height to allow the passage thereunder of the wire of which the spring 10 is made.

50 More specifically, the space 17 thus formed between the inner face of the projection 11 and the outer face 18 of the support, is substantially of the same size as or slightly larger than the diameter of the wire of the 55 spring 10. It is therefore a simple matter to insert the end 15 of the spring into said

space 17 underneath the projection 11. After this has been done, the entire spring need only be rotated bodily, thereby advancing the end 15 through the projection 60 11 and on to the surface 18.

The rotation above described, is continued until prevented by the engagement of the end 15 of the spring with the edge 16 of the strip 12 or cross bar 13, whereupon the 65 spring is locked into place by depressing said end 15 in a direction axially of said spring underneath the lowermost corner of said edge and further rotating said spring. In the case of the cross bar 13, the spring 70 becomes locked in position automatically after the end 15 has passed the edge 16, due to the upward movement of said end by reason of the spring action, as is fully pointed out in my co-pending application for Letters Patent of the United States, Serial Number 680,086 filed December 12, 1923. In the case of the strip 12, the end 15, by 75 reason of similar upward spring action passes through the next alternate opening 17 made in the strip 12 and spaced from that opening 17, through which the spring 10 was first passed, until stopped by the under surface of the projection 12. Further rotation of the spring 10, causes the end 15 to 80 pass beyond said projection and to spring out upon the surface 18.

The end 15 of the spring 10 is preferably bent upwardly to insure the spring action, above described, taking place and to prevent the ready removal of the spring by rotation in the direction opposite to that given thereto during the mounting operation. It will be seen that I prefer to space the projections 11 in such a manner, that the distance between the operative projections is somewhat greater than the diameter of the lowermost coil of the spring 10. Said lowermost coil may therefore rest firmly on the surface 18 without engaging or interfering with any of said projections excepting the one through which the spring has been passed.

It will be understood that additional projections 11 may be spaced as illustrated so as to come substantially in line with the axis of the coil spring 10 without interfering with the mounting thereof, so that only alternate projections 11 become operative in the strip 12 to lock the spring in 105 place.

It will be seen that the simplest method

by which said arch shaped projections 11 can be made is by first making a pair of parallel cuts as 14 in the surface 18 of the members 12 and 13 and then pressing 5 that portion of said bar or strip between said cuts 14 outwardly from said surface 18 to the desired height.

It will also be seen that a series of coil 10 springs 10 may be mounted on the support at any desired intervals by merely inserting the end 15 of each of the coil springs the proper number of projections 11 from the other springs.

It will be seen further that the lowermost 15 coil rests almost completely on the surface 18 of the strip 12 or the cross bar 13 whereby a firm base for said spring is provided and the spring prevented from 20 loosening or displacing itself and from departing from the perpendicular. It will be seen further that the insertion of the spring can be accomplished rapidly and effectively by unskilled labor and that once 25 assembled the spring is firmly held by tension against accidental displacement or displacement in any manner.

I claim:

1. In combination with a coil spring, means for locking said spring in position 30 comprising a support at the lower end of said spring, means pressed from said support adapted to allow the passage of said lower end of said spring therethrough, and a bent end on said spring in sprung engagement with the under surface of said support and passing through said support to the upper surface thereof for preventing relative rotative or other displacement of said spring and said support.
- 40 2. In combination with a wire coil spring, means for supporting said spring at one end thereof comprising a supporting member, and means integral with said member at the ends thereof and pressed outwardly 45 from said member at the sides thereof to provide a space between said pressed out means and the outer surface of said support, an upwardly bent end on said spring, a lowermost coil on said spring terminat-

ing in said bent end passed through said 50 space and having said end pulled downwardly out of its unstressed position into forced contact with the upper surface of said support for part of the circumference of said coil and into forced contact with 55 the under surface of said support for the remainder of the circumference, said bent end passing upwardly through said support.

3. In a support for coil springs, a series 60 of arched projections each pressed outwardly from the upper surface of said support a distance sufficient to allow the wire of the coil spring to pass between said projections and the remainder of said upper 65 surface, said projections being spaced apart a distance slightly greater than half the diameter of the lowermost coil of the coil spring, and a coil spring passed through one of said projections and in contact with 70 the upper surface of said support and pulled near the end thereof into spring contact with the under face of said support.

4. The combination with a series of wire 75 coil springs, of means for locking said springs in place comprising a spring support, means for locking part of the lowermost coil of each of said springs in pressed contact with the upper surface of said support and for locking part of said lowermost coil in pressed contact with the under side of said support comprising a series 80 of arched projections pressed upwardly from, and integral at the ends thereof with, said upper surface, said projections being 85 spaced apart a distance substantially greater than half the diameter of said lowermost coil and being adapted to have said lowermost coil passed therethrough, and an upwardly bent portion at the end of 90 said lowermost coil adapted to engage the under surface of said support, and to pass through said support from the under to the upper surface thereof at one of said projections for preventing relative rotative 95 or other displacement of said lowermost coil and said support.

ABRAHAM KRAKAUER.
